UNITED STATES PATENT OFFICE.

RAYMOND W. TIBBETTS, OF PAWTUCKET, RHODE ISLAND.

REFRIGERATING APPARATUS.

Application filed July 3, 1919. Serial No. 308,397.

To all whom it may concern:

Be it known that I, RAYMOND W. TIBBETTS, a citizen of the United States, residing at Pawtucket, in the county of Providence and State of Rhode Island, have invented certain new and useful Improvements in Refrigerating Apparatus, of which the following is a specification, reference being had therein to the accompanying drawings.

This invention relates to refrigerating apparatus in which air is compressed and expanded, in succession, and in the narrower view, the object is to provide apparatus especially suited for domestic or small scale use, and having characteristics of construction specially fitting it for such use. Accordingly, in the drawings, the invention is illustrated as embodied in apparatus 20 of that description, in which drawings,

Fig. 1 is a side elevation thereof;

Fig. 2 is a vertical section;

Fig. 3 is an end elevation partly in section; and

Fig. 4 is a detail view of the ice-preventing device.

The apparatus comprises an air compression cylinder 10 placed horizontally on top of the refrigerator, or food receptacle 11, and an expansion cylinder 12 with its axis extending at a right angle to that of the compression cylinder, and reaching down into the refrigerator compartment 13, through a hole in the top thereof and which is closed by the bed of the apparatus. Since the expansion cylinder becomes cold when the apparatus is in operation, its location within the refrigerator is very advantageous, since for some time after cessation 40 of operation of the apparatus, the cold cylinder walls or parts absorb heat and thus keep down the temperature in the refrigerator.

The compression cylinder piston 14 and 45 the expansion cylinder piston 15 are connected by connecting rods 16 and 17, respectively, to a crank pin 18 on a motor driven disk 19, the arrangement being such that the expansion cylinder delivers a maximum 50 of power at the time the compression cylinder is using a maximum of power, and thus work on the motor is reduced. The crank disk is on a shaft 20 having a sprocket wheel 21 connected by a chain 22 with a sprocket wheel 23 on the armature shaft of an electric motor 24. The switch of the latter is

operated by a thermostat (not shown) so that the motor only runs when the temperature in the refrigerator is above the degree desired to be maintained in the refrigerator. 60

In the head of the compression cylinder is an air inlet port 25 having a valve 26 opened by suction of the piston, and an eduction port 27 controlled by a valve 28, lifted from its seat by pressure from the piston on its compression stroke. Air is supplied to the inlet port by a pipe 29 having an air filter 30 containing charcoal, or some other deodorizer or air-purifying medium, which filter may be located in the refrigerator as shown, to draw warm air therefrom, or outside, or both inside and outside. With the eduction port is connected one end of a pipe coil 31, whose other end is connected to a port or passage 32 in the 75 opposite end of the compression cylinder and in the side wall of the expansion cylinder that leads to the induction port 33 in the head 34 of the expansion cylinder. The induction port 33 is controlled by a valve 35 that is opened and closed periodically by a lever 37 that acts on the valve stem 38 and is connected to one end of rod 39 whose other end is connected with an eccentric ring 40 in one side of the crank disk and thereby a to-and-fro movement is imparted to the rod. The eduction port 41 in the head of the expansion cylinder is controlled by a valve 42 that likewise is opened and closed by a lever 43 that acts on the valve stem 44; and besides its straight line motion said exhaust valve 42 has a rotary motion, produced by a ratchet wheel 45 on the stem and a pawl 46 that engages the ratchet wheel teeth and receives its motion from the 90 lever 43 to which it is attached. Below the valve 42, and quite close to it when seated, is a circular series of radially extending teeth, or pointed pins 45, which coat with the valve when it moves, to break up 100 any ice tending to form from moisture in the air, on the adjacent surfaces of the exhaust, and which if formed, chokes up the exhaust. Said pins may be attached to the valve or to the valve stem, for so located, 105 they serve to keep the parts free from ice. The location of the exhaust passage within the refrigerator diminishes the likelihood of formation of ice by freezing moisture in the air. 110

Around the compression cylinder is a water space or jacket 46, which opens at the

top into the housing 47 covering the coil 31, so that water may be circulated around the cylinder, to cool it, and around the coil, to cool air passing therethrough. Water is supplied by a pipe 48 that leads into the water jacket from a suitable source, and it escapes by an outlet pipe 49. The inlet pipe has a valve 50 with a handle or crank arm 51 from which hangs a weight 52, and on which is journalled a roller 53 that rests on the upper run of the sprocket chain 22. When the motor is not running the slack of the chain allows the weight to descend far enough to close the valve, but when the motor runs, the upper run of the chain becomes taut, and lifts the weight and the valve handle enough to open the valve and allow flow of water to the water space.

The operation of the machine will be evident from the description thus far given, and briefly, is as follows: When the temperature in the refrigerator is above the limit desired, the thermostat will start the motor, and the upper slack run of the chain 22 being tightened, the water controlling valve will be opened, thus supplying water to circulate through the water space and about the coil, to cool the compression cylinder and the air. Purified air is alternately sucked in, and expelled from the compression cylinder and forced into and through the coil, and thence into the expansion cylinder, from which in an expanded and temperature lowered state it exhausts directly into the refrigerator. The relative volumes of compression and exhaust cylinders are such that a pressure is built up and maintained in the pipe coil, and hence the latter is both an air container and an air cooling means, since it is enveloped by the circulating water. As soon as the desired low temperature is attained in the refrigerator, the thermostat automatically stops the motor.

The machine shown is very small and compact, not liable to get out of order, is inexpensive to run, and produces a very low temperature.

Of course, changes may be made from the construction shown, and, hence the scope of the invention is not to be restricted to the particular construction and arrangement of parts shown, beyond the requirements of the

language of the claims and having regard to the law as to equivalents.

What is claimed is:—

1. A refrigerating apparatus of the class described having means for compressing and expanding air, the air expanding means having a cold air exhaust port and automatic means for dislodging ice from such port.

2. A refrigerating apparatus of the class described having means for compressing and expanding air, the air expanding means having a cold air exhaust port and automatic means for dislodging ice from such port comprising spaced teeth in such port and a cooperating member.

3. A refrigerating apparatus of the class described having means for compressing and expanding air, the air expanding means having a cold air exhaust port and automatic means for dislodging ice from such port comprising a movable body in the port and spaced teeth in such port with reference to which such body moves.

4. A refrigerating apparatus of the class described having means for compressing and expanding air, the air expanding means having a cold air exhaust port and automatic means for dislodging ice from such port comprising spaced teeth in such port and a valve moving with reference to and cooperating with said teeth.

5. A refrigerating apparatus of the class described having means for compressing and expanding air, the air expanding means having a cold air exhaust port, a valve to control such port, means to reciprocate and rotate the valve, and spaced teeth in the port adjacent the valve.

6. A refrigerating apparatus having a cylinder with a motor-driven piston, a motor, a fluid supply pipe having a valve, motor-controlled means to open and close the valve comprising an endless transmitting band actuated by the motor, and a part connected with the movable member of the valve resting in contact with one of the band runs, said band run being slack when the motor is not operating and allowing movement of the movable valve member to close the valve.

In testimony whereof I affix my signature.

RAYMOND W. TIBBETTS.
